UNITED STATES PATENT OFFICE.

JOHN D. BOWNE, OF NEW YORK, N. Y., ASSIGNEE OF ONE-HALF TO JOHN WALLACE
SLAWSON, OF NEW YORK, N. Y.

ELECTRIC DAMPER-REGULATOR.

No. 872,893.

Specification of Letters Patent.

Patented Dec. 3, 1907.

Application filed November 15, 1906. Serial No. 343,614.

To all whom it may concern:

Be it known that I, JOHN D. BOWNE, a citizen of the United States, residing at New York, in the county of New York and State 5 of New York, have invented certain new and useful Improvements in Electric Damper-Regulators, of which the following is a specification.

My invention relates to electric damper 10 regulators, and belongs directly in that class of apparatus, each example of which includes an electric motor as the operating means, with a divided function, the office of the motor being in part to control the position and movement of the damper, and in part to throw an electric switch affecting the motor current.

The object of my invention is to produce 15 damper-operating mechanism allied to the type mentioned, and designed particularly for use in connection with high pressure steam sources or systems, wherein a slow-moving electric pilot switch is adapted to make and break the current from a relatively 20 inexpensive low-tension battery that energizes suitable magnets arranged to turn a quick-moving reversing switch included in the normal street circuit by which the motor is served, such mechanism being, as an additional 25 object of my invention, special in constructive form and arrangement.

To carry out the objects stated, parts are fashioned and associated as illustrated in the accompanying drawings, of which

35 Figure 1 represents a side view of all the elements assembled. Fig. 2 is a top plan view of the low-tension switch. Fig. 3 is a top plan view of the high-tension switch, and shows in diagrammatic form the arrangement 40 of the switch, motor and electrical conductors.

Like reference letters are used to designate like parts throughout the specification and drawings.

45 In the frame A of any suitable casing, is supported the main shaft B in bearings b. The shaft is provided with a worm b' near its inner end, and it is driven by the motor b'.

The worm drives a reducing gear C, and 50 the pinion c on the same shaft with the gear C, still further reduces the speed by its engagement with arm gear D. The movement of gear D, by means of the sprocket d on the same shaft, and chain d' is transmitted to damper E through its sprocket e, all

of suitably relative sizes and positions for the purposes desired.

As stated, the motor is included in the street circuit, the conductors being designated b³, and there is likewise connected in the motor circuit the lamp b⁴, or other desired resistance, when it is needful to defend the motor against a street current of excessive strength. It will be noted that the current is thrown upon the motor oftentimes 60 when the armature is at rest. A certain advantage follows from the introduction of the lamp, which is that when the light is seen to glow with regular brilliancy and at customary intervals it is indicative of the proper 65 working of the apparatus.

In Fig. 3 it is shown that the main terminals of the motor are each connected to two mercury cups, and that the two cups thus connected with each terminal lie on opposite 70 sides and beneath different ends of the rocking, reversing switch F. Thus, cups G and K are connected with one motor terminal, and cups J and H with the other, the cups G and J being under one extremity of switch 75 F, and cups H and K being situated under the other end of that switch. The ends of the switch are formed of blocks of insulation f and f', and the fingers g and j are secured to block f and are plunged into cups G and J. 80 At the other end of the switch the fingers h and k are secured to block f' and plunge into cups H and K when the switch rocks. In Fig. 3 it is also illustrated that each of the street circuit conductors b³ is connected to 85 two of the fingers, one at each end of the switch F. That is to say, for example, the positive wire from the street is connected with fingers g and h, and the negative wire with fingers j and k. By reason of the particular arrangement of conductors and switch and motor terminals, it is believed to be now discernible that as the ends of switch 90 F are alternately lowered the street current is sent through motor b² in opposite directions, in other words, the motor is first operated in one direction and then reversed. The thumb-screws f² and the springs f³ are provided to yieldingly balance switch F 95 with all fingers raised from the mercury cups and all motor connections broken.

To rock the switch, two magnets are introduced as shown in Fig. 1 and referred to by letters L and M. They are arranged to act alternately upon a common armature N 100

110

which caps transversely the post f^4 projecting upwardly from switch F. The magnets are energized by local, low-tension circuits in the conductors O, including the battery P. The battery circuit is made by the rocking, pilot switch Q, pivotally supported at its middle point, and provided with the forks g and g' at its ends. The switch is rocked by the flattened and bent tube R, having one end rigidly connected with the hollow support r and open to boiler steam entering through pipe r' . The other end of the tube is free to move and is closed. It is limited in its movement by the adjustable thumb-screws r^2 , and it is coupled pivotally by means of the rod r^3 with the crank q^2 attached to switch Q at its pivotal point and adapted to rock the switch as the pressure, rising or falling in tube R, tends to straighten or permit it to curve in the usual manner. As the switch Q rocks, the forks g and g' are dipped alternately into pairs of mercury cups, one pair of cups being supported at each end of the rocking beam S that is pivoted at the middle as shown. The pairs of cups on the ends of the beam are marked s , and s' . Beam S is rocked by means of its crank s^2 , which is pivotally connected by rod d^2 with the wrist d^3 eccentrically carried by the hub or center of gear D.

The mode of operation of this invention is the following: At normal steam pressure the curved tube R holds switch Q approximately level and no connections are made. An excess of steam pressure rocks switch Q and dips fork g into the cups s , closing the local circuit and energizing magnet L. Fingers g and j at once plunge into cups G and J and the motor starts, resulting in the relatively slow turning of gear D in the direction of the arrow, and in a closing movement of damper E. Rod d^2 is drawn to the left and by crank s^2 rocks downwardly the end of beam S which carries the cups s . If this movement continues, the local circuit will obviously be broken and the motor stopped, unless the steam as constantly increases in pressure and rocks low-tension switch correspondingly. When, however, the tube reaches its limiting thumb-screw, the lowering of cups s just explained necessarily breaks the circuit. Such is an extreme instance, however, because the damper E has been concurrently closed and the draft stopped. The breaking of the local circuit halts the motor and leaves the remaining parts as they may be, but the fall of pressure soon curves the tube R and dips fork g' into cups s' thus energizing magnet M and plunging fingers h and k into cups H and K, when, as explained, the motor again starts but in reverse direction and the contrary movement of the parts opens the damper. The movement proceeds until the renewed pressure or the rocking of beam S breaks the local circuit. It is thought to be now clear

that the switch Q rocks slowly, and, no sparking occurs because the local circuits transmit a low tension current. It is also believed to be made out that the high-tension switch F rocks quickly, as it must by reason of the essential action of the magnets, and no sparking occurs because the make and break of the street current is quickly effected. As intimated above, the opening and closing movements of the damper are gradual and occur upon relatively small variations of temperature.

Having now described my invention and explained the mode of its operation, what I claim is—

1. In a damper regulator, the combination with the damper, of electro-magnetic mechanism adapted to operate the damper, a switch device comprising a pivoted switch, pressure-actuated means arranged to move the said switch, pivotally supported switch contacts, and connections whereby the said mechanism moves the said switch contacts, a second switch, and electrical switch-operating means arranged to act upon the said second switch, the said switch-operating means being in circuit with and controlled by the said switch device, and the said second switch being arranged to make and break the circuit of the said electro-magnetic mechanism.

2. In a damper regulator, the combination with the damper, of a reversible electric motor and mechanism adapted to operate the said damper, a reversing switch device comprising a pivoted switch, pressure-actuated means adapted to move the said switch in two opposite directions, pivotally supported switch contacts, and connections whereby the said damper-operating mechanism moves the said switch contacts, a second reversing switch, and electrical switch-operating means arranged to act upon the said second switch, the said switch-operating means being in circuit with and controlled by the said switch device, and the said second switch being arranged to make and break and reverse the circuit of the said electric motor.

3. In a damper regulator, the combination with the damper, of electro-magnetic mechanism adapted to operate the damper, a switch device comprising a pivoted switch, a pressure-actuated curved tube arranged to move the said switch, pivotally supported switch contacts, and connections whereby the said mechanism moves the said switch contacts, a second switch, and electrical switch-operating means arranged to act upon the said second switch, the said switch-operating means being in circuit with and controlled by the said switch device, and the said second switch being arranged to make and break the circuit of the said electro-magnetic mechanism.

4. In a damper regulator, the combination

- with the damper, of a reversible electric motor and mechanism adapted to operate the said damper, a reversing switch device comprising a pivoted switch, a pressure-actuated 5 curved tube adapted to move the said switch in two opposite directions, pivotally supported switch contacts, and connections whereby the said damper-operating mechanism moves the said switch contacts, a second 10 reversing switch, and electrical switch-operating means arranged to act upon the said second switch, the said switch - operating means being in circuit with and controlled by the said switch device, and the said second 15 switch being arranged to make and break and reverse the circuit of the said electric motor.
5. In a damper regulator, the combination with the damper, of electro-magnetic mechanism adapted to operate the damper, a switch device including a switch, expandible 20 means constructed and arranged to move the said switch, pivotally supported switch contacts, and connections whereby the said mechanism moves the said switch contacts, a second switch, and electrical switch-operating means arranged to act upon the said second 25 switch, the said switch - operating
- means being in circuit with and controlled by the said switch device, and the said second 30 switch being arranged to control the circuit of the said electro-magnetic mechanism.
6. In a damper regulator, the combination with the damper, of electro-magnetic mechanism adapted to operate the damper, a switch device including a switch, expandible 35 means constructed and arranged to move the said switch, pivotally supported switch contacts, and connections whereby the said mechanism moves the said switch contacts, a second switch, and electrical switch-operating means arranged to act upon the said second switch, the said switch - operating 40 means being in circuit with and controlled by the said switch device, and the said second switch being arranged to control the circuit of the said electro-magnetic mechanism.
5. In testimony whereof I affix my signature 45 in presence of two witnesses.

JOHN D. BOWNE.
